US00D848906S

(12) **United States Design Patent** (10) **Patent No.:** **US D848,906 S**
(45) **Date of Patent:** **** May 21, 2019**

- (54) **SERVICEABLE REPLACEMENT SPINDLE**
(71) Applicant: **Axle Tech Inc.**, Claremore, OK (US)
(72) Inventor: **Todd Carroll**, Claremore, OK (US)
(73) Assignee: **UA HOLDINGS, INC.**, Claremore, OK (US)
(**) Term: **15 Years**
(21) Appl. No.: **29/667,445**
(22) Filed: **Oct. 22, 2018**
